(57) **CLAIM**

The ornamental design for packaging for sensing accessory, as shown and described.

DESCRIPTION

FIG. 1 is a front view of packaging for sensing accessory embodying our new design shown in an open position; FIG. 2 is a rear view thereof shown in an open position; FIG. 3 is a bottom view thereof shown in an open position; FIG. 4 is a top view thereof shown in an open position; FIG. 5 is a side view thereof as seen from the right-hand side of FIG. 1; FIG. 6 is a side view thereof as seen from the left-hand side of FIG. 1; FIG. 7 is a bottom perspective view thereof shown in an open position; FIG. 8 is a top perspective view thereof shown in an open position; FIG. 9 is a front view thereof shown in an open position with a closed tab and a sensor positioned in the packaging, the sensor and portion of the tab not forming any part of our claimed design;

FIG. 10 is a front view thereof shown with a closed tab and in a partially closed position;

FIG. 11 is a front view thereof shown with a closed tab and in a partially closed position;

FIG. 12 is a front view thereof shown with a closed tab and in a closed and secured position; and,

FIG. 13 is a rear view thereof shown with a closed tab and in a closed and secured position.

The broken lines shown represent unclaimed subject matter and form no part of the claimed design.

1 Claim, 11 Drawing Sheets
